UNITED STATES PATENT OFFICE

WALTER B. MACAULAY, OF OAKLAND, CALIFORNIA, ASSIGNOR TO YUBA MANUFACTURING COMPANY, OF SAN FRANCISCO, CALIFORNIA, A CORPORATION OF CALIFORNIA

DREDGE

Application filed June 2, 1930. Serial No. 458,986.

My invention relates to dredges adapted to operate on bodies of water, either natural or artificial, for the purpose of removing earth or similar material from beneath the surface of the water. Dredges of this type usually comprise a hull on which the dredging machinery is located and which is positioned for operation by means of cables extending from the hull to suitable points of anchorage. A plurality of such cables customarily are used and there is ordinarily provided on the hull machinery for hauling in or paying out selected ones of the cables in order to locate the dredge for the most advantageous operation and also for propelling the dredge from one location to another on the body of water. Dredges of the type mentioned are of considerable size and the mechanism for handling the cables and for maneuvering the dredge is usually heavy and relatively difficult to operate, not only because of its massiveness but also because of its relative complexity and of the numerous controls necessary. Such dredges often are utilized in localities, such as tropical countries, in which the class of labor available for operation is not of the highest and in which the climate all but precludes strenuous physical labor of any character. In the past in order to operate at all, even with indifferent success, it has been necessary to employ a large crew of operators usually with each operator assigned to a particular duty in connection with the handling of cables for positioning the dredge. Not only is the physical labor involved in such operation considerable but also numerous difficulties arise with respect to accurate and precise maneuvering of the dredge by virtue of the fact that the class of labor is inferior and the difficulty of communication from the chief operator to his assistants is great.

It is therefore an object of my invention to provide a dredge in which the maneuverability of the dredge is improved over previous practice.

Another object of my invention is to provide a dredge which can be maneuvered with a very much smaller crew than usual, in the

preferred case but a single operator being necessary.

A further object of my invention is to provide mechanism for controlling the dredge of such a nature that the physical effort involved in operation is reduced to a minimum.

An additional object of my invention is to provide a power operated dredge control such that no damage can occur if the power supply should fail.

The foregoing and other objects are attained in the embodiment of the invention shown in the drawings, in which

Fig. 1 is a side elevation of a portion of the cable drums included in the dredge showing the pneumatic actuators therefor.

Fig. 2 is a plan of the mechanism disclosed in Fig. 1.

Fig. 3 is a plan of an additional cable drum with its controls and a speed change mechanism and associated controls.

Fig. 4 is a diagrammatic showing of the piping arrangement employed with the pneumatic control scheme incorporated in my invention.

Figure 5 is an enlarged plan of a typical brake linkage.

In its preferred form, the dredge of my invention includes a cable drum connected to a source of power through a clutch and provided with a brake for frictionally constraining the cable drum, the clutch and the brake being operated by pneumatically expandable chambers under control of an operator from a single remote point.

Although the dredge of my invention can be embodied in a number of different forms depending upon the surrounding conditions I have chosen to disclose it herein in a form which has met considerable success in practice. A dredge constructed in this fashion is being operated with great advantage in a tropical country.

Aboard the hull of the dredge there is provided a framework 6, conveniently constructed of structural shapes, which provides a support for a plurality of cable drums. Of these drums, the starboard bow line drum 7 is mounted adjacent one end of the framework in journals 8 and 9. A clutch 11 is preferably

provided which is capable of connecting the drum 7 to or disconnecting it from a gear 12. The clutch is of any preferred type and is provided with an actuating collar 13 which in one position permits engagement of the clutch to transmit power from the gear 12 to the drum 7 and in another position disengages the clutch to prevent the transmission of power from the gear 12 to the drum 7.

10 Also associated with the starboard bow line drum 7 is a brake 14 of any desired kind and in the present instance comprising a friction band engageable with the drum 7 to constrain undesired rotation thereof. The brake 14 is controlled through a lever 16 so that in one position of the lever the brake is applied and in another position of the lever the brake is released.

15 Arranged on the framework 6 parallel to the drum 7 is a port bow line drum 17 mounted on a shaft 18 journalled in bearings 19 and 21 secured to the framework 6. The port bow line drum 17 is provided with a clutch 22 operated by a clutch collar 23 in the customary fashion, and is provided with a brake 24 responsive to a brake lever 26. The drum 17 is connected through clutch 22 with a gear 27 mounted on the shaft 18 and meshing with gear 12.

20 25 In a similar fashion, a starboard stern line drum 28, journalled as at 29 and 31 on the framework 6, is provided with a clutch 32 controlled by a clutch collar 33 and is provided with a brake 34 actuated by a brake lever 36, so that the drum 28 can be connected or disconnected, as desired, from shaft 37 mounted in the journals 29 and 31 and can be retarded frictionally by means of the brake 34. A gear 38 is connected to the shaft 37 and meshes with gear 27.

30 35 In a comparable manner a port stern line drum 39 is freely rotatable on a shaft 41 mounted in bearings 42 and 43 on the framework 6. For connecting the shaft 41 with the drum 39 a clutch 44 is provided which is actuated through the medium of a clutch collar 46. The drum 39 is likewise provided with a brake 47 actuated by a brake lever 48 while power is transmitted to shaft 41 by a gear 49 meshing with gear 38 and likewise meshing with a pinion 51 secured at the extremity of a shaft 52 which in turn is journalled as at 53 and 54 in the framework 6.

40 45 50 In parallelism with the drums previously described is a head line drum 56 freely rotatable on a shaft 57 mounted in bearings 58 and 59 on the framework 6 and carrying at one extremity a bull gear 61. At one side of the head line drum 56 is a brake 62 controlled through a brake shaft 63 for selectively offering frictional retardation to the drum 56.

55 60 65 Meshing with bull gear 61 and freely rotatable on shaft 52 is a pinion 64 connected to the driven member of a clutch 66 likewise mounted on shaft 52. The driving member

of clutch 66 is controlled through a collar 67 for connecting or disconnecting the clutch to impart rotation to the pinion 64 from the shaft 52 at the will of the operator.

70 I preferably drive the shaft 52 at either selected one of a plurality of speeds, in the present instance a two speed drive being indicated. Mounted on shaft 52 is a gear 68 which meshes with a pinion 69 fast on a shaft 71 journalled at 72 and 73 in an auxiliary frame 74. Also mounted on shaft 71 is a gear 76 and a larger gear 77. The gear 76 meshes with a gear 78 of approximately the same pitch diameter freely rotatable on a shaft 79 journalled at 81 and 82 in the auxiliary frame 74. Meshing with the gear 77 is a pinion 83 of considerably smaller pitch diameter which likewise is freely rotatable on shaft 79. In order to transmit driving power from shaft 79 through gears 78 and 76 as a unit or optionally through gears 83 and 77 as a unit in order to provide two different speeds of drive for the shaft 52, I mount a pair of clutches 86 and 87 on the shaft 79 for alternative engagement with the gears 78 and 83 respectively.

75 80 85 90 95 In accordance with my invention I provide means for selectively actuating any desired one or any desired plurality of the various clutches and brakes heretofore described. The operating means is preferably pneumatic so that the actual force required of the operator to operate any one or more of the units is derived from a mechanical source and is independent of substantial human labor. Furthermore, I provide controllers for the various units in such a fashion that the pneumatic force available is controlled from a single point or location, usually remote from the line drums described, and convenient for actuation by the chief operator of the dredge.

100 105 110 115 120 At a suitable place on the hull of the dredge I provide a source of pneumatic pressure such as an air compressor 91 for maintaining an air reservoir 92 in operating condition. A main conduit 93 leads from the reservoir 92 to the control house or other selected point on the dredge for centralized operation. Connected to the main 93 is a clutch control valve 94 which in one position of the controller such as 96 diverts air from the main 93 into a duct 97 leading to a pneumatically expandable chamber 98 which is connected to the clutch collar 67 of the head line drum 56 and is effective when expanded to engage the clutch for transmitting power from shaft 52 to the pinion 64 to rotate the drum 56 in accordance with the rotation of the shaft.

125 130 135 In another position of the controller 94, a position such as 99, for instance, air is taken from the main 93 and is passed through a conduit 101 leading to a pneumatically expandable chamber 102 which, when expanded,

operates the clutch collar 67 to release or disengage the clutch 66 so that no power is transmitted between the shaft 52 and the head line drum 56. By virtue of this arrangement there is under control of a single operator the entire operation of the clutch controlling the functioning of the head line drum.

To supplement the power drive and to afford an additional control over the drum 56 I provide a pneumatically expandable chamber 103 which is connected to the brake shaft 63. Also connected to the shaft 63 is a weight 104 for normally biasing the shaft so that the brake is urged toward applied position. Upon expansion of the chamber 103 the weight 104 is lifted and the shaft 63 is actuated to release the brake 62. Thus the weight 104 is normally effective to apply the brake so that in the event no compressed air is available the drum 56 cannot inadvertently be rotated. For expanding the chamber 103 I connect it through a conduit 106 with a brake controller 107 preferably provided with a gauge 108 and receiving pneumatic pressure from the main 93. The controller 107 is such that pneumatic pressure can selectively be applied to the chamber 103 to operate the brake 62 in the desired manner and amount.

In a similar fashion on the port bow line drum 17 I provide pneumatic chambers 107' and 109' leading respectively through conduits 109 and 111 to a clutch controller 112 receiving air from the main 93 and capable of transmitting pneumatic pressure selectively to the chambers 107' and 109' for shifting the clutch collar 23 to engaged or disengaged position of the clutch. There is also provided an expandable chamber 113 connected to the brake lever 26 for operating the brake which can, if desired, be furnished with unidirectional bias weights, as previously described. The chamber 113 receives pressure through a duct 114 leading to a brake valve 116 at the selected point of control, the brake valve being supplied with pneumatic pressure from the main 93.

The starboard stern line drum is likewise connected by its clutch collar 33 to pneumatically expandable chambers 117 and 118 respectively connected through ducts 119 and 121 to a clutch controller 122 receiving air from the main 93 and capable of transmitting the pneumatic pressure selectively to either of the chambers 117 and 118. The brake lever 36 of the starboard stern line drum 28 is connected to a pneumatically expandable chamber 123 provided with a conduit 124 leading to a brake controller 126 also connected to the main 93 and capable of expanding or contracting the chamber 123 at the will of the operator. Biasing means, such as the described weights, are optionally utilized with brake 34.

In a similar fashion the port stern line drum 39 is provided with a pair of pneumatically expandable chambers 127 and 128 connected to the clutch collar 46 and communicating through ducts 129 and 131 with a clutch controller 132 receiving pneumatic pressure from the main 93 and capable of selectively expanding the chambers 127 and 128 to control the clutch 44. A brake chamber 133 of the same pneumatically expanding type is joined to the brake lever 48 and is connected through a conduit 134 to a brake controller 136 joined to the supply main 93 and effective to apply or release brake 47 on drum 39. In this case, also, biasing means optionally maintain the brake normally applied.

The starboard bow line drum clutch 11 is controlled by a pair of pneumatic chambers 137 and 138 connected through ducts 139 and 141 with a clutch controller 142 in communication with the main 93 and having two positions to control selectively the chambers 137 and 138 to actuate the starboard bow line drum clutch in the desired fashion. The associated brake 14, optionally biased to applied position, is actuated by an expandable chamber 143 joined by a pipe 144 to a controller 146 communicating with main 93.

Not only do I control the various cable drums pneumatically in accordance with my invention but I also operate the head line drum pneumatically and the change speed gearing in a similar fashion. The speed clutches 86 and 87 are simultaneously controlled in opposite sense by a pair of pneumatically expandable chambers 147 and 148 which are connected through pipes 149 and 151 to a clutch controller 152 joined to the main 93 and capable of causing the chambers 147 and 148 selectively to expand for engaging either the clutch 86 or the clutch 87 to transmit the power at the desired speed ratio.

In accordance with my invention I have provided on a dredge means for controlling a plurality of line and speed change clutches and brakes from a remote point at which all of the controls are grouped so that a single operator with the expenditure of a minimum amount of physical energy can control exactly and to a nicety and without the necessity of communicating his desires to other operators the entire maneuvering and operation of the dredge. Furthermore, in accordance with my invention, upon the failure of pneumatic pressure, or the ultimate source of power, from any cause whatsoever the dredge is not permitted to shift its position or to wreck itself but the drum brakes are all automatically applied and the dredge held in place pending proper resumption of operations.

It is to be understood that I do not limit myself to the form of the dredge shown and described herein, as the invention, as set forth

in the following claim may be embodied in a plurality of forms.

I claim:

- 5 A dredge comprising a cable drum, means for driving said cable drum, a change-speed gear interposed between said driving means and said drum, a clutch interposed between said change-speed gear and said drum, means including a first pneumatically expandible chamber for engaging said clutch, means including a second pneumatically expandible chamber for disengaging said clutch, a brake for frictionally constraining said cable drum, means for normally applying said brake, means including a third pneumatically expandible chamber for releasing said brake, means including a fourth pneumatically expandible chamber for operating said change-speed gear in one position, means including a fifth pneumatically expandible chamber for operating said change-speed gear in another position, and grouped pneumatic controllers for controlling said first to fifth, inclusive, of said expandible chambers.
- 10 20 25
- 25 In testimony whereof, I have hereunto set my hand.

WALTER B. MACAULAY.
